UNITED STATES PATENT OFFICE.

EMANUEL W. DUNN, OF SAN FRANCISCO, CALIFORNIA.

ORCHARD-HEATER.

1,165,326.

Specification of Letters Patent. Patented Dec. 21, 1915.

Application filed July 27, 1914. Serial No. 853,331.

To all whom it may concern:

Be it known that I, EMANUEL W. DUNN, a citizen of the United States, residing in the city and county of San Francisco and State of California, have invented new and useful Improvements in Orchard-Heaters, of which the following is a specification.

This invention relates to orchard heaters.

The object of this invention is to provide

10 a simple, practical combustion and smoke consuming stack for orchard heaters and by which air is efficiently mixed with the rising vapors or gas to produce perfect combustion and in and at such a position on the heater that the maximum heating effect is obtained and distributed over a large area; to provide an improved stack readily adaptable to any type of heater; and to provide 15 an orchard heater, the fuel of which may be readily and safely ignited.

The invention consists of the parts and the construction and combination of parts as hereinafter more fully described and claimed, having reference to the accompanying drawings, in which—

Figure 1 is a side elevation, partly broken away and part in section, of the heater with its cover in place. Fig. 2 is a side elevation of the heater, partly broken away. Fig. 3 30 is a detail of the stack lock. Fig. 4 is a side elevation of a fragment of the stack showing an air inlet duct. Fig. 5 is a section on line 5—5, Fig. 4. Fig. 6 shows an adapter whereby the stack is secured to another type of receptacle.

2 is a suitable receptacle for holding liquid or other fuel, closed by a suitable cover 3, with a vapor or gas outlet 4, and having a stack 5 which projects upwardly from the 40 cover.

Any suitable means may be utilized to provide for the admission of air into the receptacle below the cover, one form of which is disclosed as a perforated tube 6 45 projecting down through and supported on the cover. The upper open end of the tube 6 is covered by a cap 7; having a shutter 8 movable to cover and uncover the apertures in cap 6 to control the down draft of air. Further control of fresh air inlet is had by an auxiliary regulator 9 covering a radial passageway 10 leading to the vapor outlet 4.

For convenient, ready and safe lighting 50 of oil in the receptacle, a wick 11, of suitable material such as asbestos, may be hung in

the draft tube 6 with its upper end at an opening of the cap 7. To ignite the fuel a little gasolene or other oil may be poured on the wick and a flame applied. The heat 60 collecting in the receptacle will vaporize the fuel and the hot gaseous fumes will rise and enter the stack 5. The rate of generation is controlled by the shutter 8 and the regulator 9.

An important feature of this invention is the means by which the admission of air into the stack is had and controlled for the perfect combustion of the generated vapors or gases and elimination of undesirable smoke 70 and soot residue, and by which the maximum heating efficiency of the combustion is obtained. To this end the stack 5, which is here shown of telescopic sections 5^a, 5^b and 5^c, though it may be of a single piece of suitable proportions, is provided at a suitable portion with air ducts 12, in this instance formed by punching the metal of the stack and bending in (Figs. 1, 2, 3 and 5) the tongues 14, thus at once forming an aperture 80 12, Figs. 4 and 5, to let air in and forming a means (tongue 14) to direct the stream of air upwardly. This is of dual advantage; first, the tongues prevent the direct transverse flow of air from one side of the stack to and out at the other, taking with it valuable vapor or gas; and, second, the moving jets or streams of air deflected upwardly by the duct wall act inductively upon the fumes therebelow in the stack and so accelerate 90 their rate of upward flow to the zone of the air streams. The rate of flow of air into the ducts or jet devices 12 is controlled to a nicety by a suitable closure or perforated damper 15 movable on the stack to cover 95 the apertures 13.

Higher in the stack than the circumferential ducts 12, which are staggered, are air inlet holes 16, over which is movable a perforated band or damper 16' to control the 100 in-draft. The function of the apertures 16 is to allow a cross draft of air in the stack above the jet devices 12, this cross draft acting as a fluid check or stop to intercept the rising gaseous fumes from the receptacle 105 2. Thus by the induction means or nozzle-like deflecting tongues 14 an upward movement of fumes is had with a speed accelerated over that which would obtain without the devices 12; and in addition to this the 110 inlet holes 15 provide for a cross draft of fresh air in such regulated quantities as to

produce a perfect mixture in the stack. This mixture is then effectually and completely burned in and through the stack to the top and the heat due to combustion internally of the stack is rapidly and extensively radiated by the latter in a manner greatly superior to heaters in which the greatest part of the combustion occurs above the stack and where the heat generated rises vertically with little or no beneficial radiation. In other words, the present heater operates by internal perfect combustion to radiate over a large adjacent area a greater amount of heat than heaters without this structure. It is understood that the jet forming ducts may be of any suitable kind. While the nozzle tongues 14 are shown as with rounded ends and as concaved, it is understood that their form may be varied, 20 as desired.

For controlling the escape of the gases from the receptacle into the stack a throttle plate or spreader disk 17 is suitably arranged adjacent to the vent 4, whereby the 25 gases are made to travel through a ring opening around the plate and to be forced out adjacent to the stack wall to insure proper mixing with the incoming air through 10, 12 and 16, and also to throw the heat 30 outward and increase the temperature of the radiating surface. The stack 5 may be detachably locked to the cover by any suitable means, as a pin and slot device 18, shown in detail in Fig. 3, and to fit the stack 35 to a different type of heater receptacle an adapter or collar 19 is shown in Fig. 6.

When a sectional stack, as shown, is utilized, it may be telescoped for compactness and covered with a tubular cowl 20 with a 40 flaring cape 21, whereby the entire upper surface of the heater is inclosed to keep out moisture and dirt when the heater is unused. For a temporary cover a cap 22 is provided to fit the top of the stack. When the stack 45 is to be extended for use, the sections are firmly seated at their joints readily by passing a piece of wire or iron 23 through the outside top section 5^c and pulling them up firmly.

50 The stack, whether sectional or unitary, may be readily and efficiently utilized upon any type of heater providing for the generation of a combustible vapor or gas from the fuel and which is directed into the stack. 55 Thus I provide a stack with means for admitting a quantity of air which is divided into a plurality of small, upwardly directed streams or jets readily mixing with the more or less compact, upwardly moving column of 60 vapor in the stack and generated from the fuel. These streams of air quickly mix with the vapor and produce a perfectly combustible mixture, thereby consuming all carbon and producing a smokeless fire. It is 65 understood that this stack and smoke con-

sumer is readily adaptable to many types of orchard heaters manufactured and in use.

Having thus described my invention, what I claim and desire to secure by Letters Patent is—

70 1. The combination with an orchard heater vessel adapted for the generation of vapor from oil therein, of a stack disposed upon the heater vessel to receive the vapor, means on the stack whereby air is directed inwardly and upwardly to mix with the rising vapor in the stack, the latter having apertures for admitting air in a draft across the rising mixture, and means intermediate the stack length for regulating both the up-draft of air and the cross draft of air.

75 2. A stack, for orchard heaters having a receptacle adapted for the generation of vapor from oil therein, with adjustable, circumferential means intermediate its length 80 for directing air inwardly and upwardly to mix with the vapor rising through the stack from the receptacle, said means including inclined tongues punched inwardly and arranged to direct air from without the stack 85 inwardly.

90 3. The combination in a covered orchard heater, of an oil receptacle adaptable for the generation of vapor from the oil, means for supporting combustion of oil within the receptacle, and a collapsible combustion stack formed of a series of upwardly flaring sections, the smallest of which is attached to the cover, said stack being provided with 95 openings for the admission of air to mix with the rising vapor.

100 4. The combination in an orchard heater, of an oil receptacle for the generation of vapor from the oil, a collapsible combustion stack, having sections coöperating, when the stack is extended, to form tight self-sustaining joints, and means detachably securing the lower section to the receptacle, said stack having means for directing air inwardly and upwardly to mix with the vapors.

105 5. The combination in an orchard heater, of an oil receptacle for the generation of vapor from the oil, a collapsible combustion stack, having sections coöperating, when the stack is extended, to form tight self-sustaining joints, means detachably securing the lower section to the receptacle, said stack having means for directing air inwardly and upwardly to mix with the vapors, and having 110 perforations for providing a cross draft above the zone of mixture in the stack.

115 6. The combination in an orchard heater, of an oil receptacle for the generation of vapor from the oil, a collapsible combustion stack, having sections coöperating, when the stack is extended, to form tight self-sustaining joints, means detachably securing the lower section to the receptacle, said stack having means for directing air inwardly and upwardly to mix with the vapors, and hav-

ing means for providing a cross draft above the zone of mixture in the stack, and for regulating the up and cross drafts.

7. The combination in a covered orchard heater, of an oil receptacle adaptable for the generation of vapor from the oil, a combustion stack having sections collapsible to rest upon the cover, and a cowl having a cap to cover the receptacle and a tubular body 10 to cover the collapsed stack and also covering the receptacle top.

8. An orchard heater comprising a covered receptacle having an aperture in the cover for the inlet of air to support combustion of oil within the receptacle, an obliquely arranged tube within the receptacle in communication with said aperture, a wick extending through said tube with one end adjacent to the aperture and adapted to be 20 ignited throughout its full length, and a combustion stack carried on said receptacle.

9. The combination in an orchard heater, of a covered receptacle for fuel oil, a col-

lapsible stack therefor, comprising a plurality of tapering sections and having means 25 for controlling and admitting drafts of air into the stack, and a throttle plate suspended below the lower end of the stack for controlling the issue of vapor thereinto.

10. The combination in an orchard heater, 30 of a covered fuel receptacle having a vapor outlet and a stack of larger diameter at the upper end, with the smaller end fitting over the vapor outlet, said stack being made in telescoping sections to collapse one over the 35 other without removal from the receptacle, and each section resting on the cover when collapsed.

In testimony whereof I have hereunto set my hand in the presence of two subscribing 40 witnesses.

EMANUEL W. DUNN.
